UNITED STATES PATENT OFFICE.

VICTOR G. BLOEDE, OF BALTIMORE, MARYLAND, ASSIGNOR OF ONE-HALF
TO JOHN BANCROFT, OF WILMINGTON, DELAWARE.

PROCESS OF TINTING FABRICS.

SPECIFICATION forming part of Letters Patent No. 394,446, dated December 11, 1888.

Application filed July 13, 1886. Serial No. 207,931. (Specimens.)

To all whom it may concern:

Be it known that I, VICTOR G. BLOEDE, a citizen of the United States, and a resident of the city of Baltimore and State of Maryland, have invented certain new and useful Improvements in Processes for Tinting Fabrics and Fibers, of which the following is a full, clear, and exact specification.

Heretofore it has been customary to tint fibers and fabrics by immersing them in a solution of soluble coloring-matter, almost all of which are to a greater or less extent deteriorated by the action of sunlight and dampness and caused to fade. The principal materials which can be used for dyeing and which can well withstand the action of the elements without deterioration are the mineral earths, elements, and most compounds which are insoluble in water. I have discovered a method by which these insoluble compounds which have fast-color properties in the presence of both light and water may be used to tint fibers and fabrics, so as to give them a tone of color and superficial appearance as smooth, clear, and perfect as can be obtained by the most permanent vegetable or organic dyes.

I have found that many insoluble colors have the property when in a state of very fine subdivision of uniting with or attaching themselves to or permeating a fiber in such a manner as to tint the fiber of a fabric evenly, and in some cases permanently, and to produce a product which, so far as physical properties are concerned, is very similar to, if not identical with, a fabric tinted by the methods of dyeing where the coloring compound is dissolved, the fabric impregnated with it and then treated with a precipitant.

I find that to accomplish my results in the most satisfactory way it is necessary to reduce my insoluble color to a state of very great subdivision. I find that the most satisfactory method of preparing my color, because it is the one that gives the most homogeneous and perfect division of the color, when the nature of the color to be employed permits of it, is precipitation of the coloring compound from a dilute solution, either in pure water or in water mixed with a soluble gum. I have also gotten some good results by grinding dry color in water and repeatedly floating it, and also by grinding a dried

precipitate or solid color in the presence of viscous matter. The viscous matter, when used in conjunction with the precipitation or in the grinding process, seems to have the effect of holding the color particles apart from one another during the process of subdivision, and also when divided, and preventing the aggregation of them. As a general rule, the shades used are the result of a mixture of several insoluble compounds in a state of fine subdivision, each prepared by the method just described. The difference of specific gravity of these elements of a shade will cause them, when suspended in a pure aqueous solution and allowed to stand, to separate and settle more or less and destroy to some extent the shade originally prepared. This also is prevented by the employment of viscous matter in the solution, which serves to hold up the color and prevent any element of it from settling.

The test of fineness that I have found successful is the practical one of experimenting from time to time with the color by applying to the fabric it is desired to dye—that is to say, by passing a piece of the fabric through the color-bath in which the color is suspended. If upon subsequent drying and washing it is found that the color is dislodged to any material extent, the subdivision of the color is continued and similar experiments are from time to time made with it until it is found that the pieces of the fabric are uniformly and permanently dyed, and the color will not yield more than is desired to washing.

In making the tests above alluded to care must be taken to secure pieces of fabric which are entirely free from oily matter, and also that the solution in which the color is suspended is an aqueous one, because while for the complete permeation of a fiber or fabric, as well as for the permeation and permanent fixation of the color, it is necessary to have the color in a state of subdivision equally fine, still many causes—such as the presence of a little oil in the fabric or a little oil in the bath—will often prevent the color from being fast, but not interfere with its complete permeation of the fiber. For this reason it is necessary to test the color for fastness by supplying the conditions under which fastness can be accomplished, in order to determine whether

er the color is in a state sufficiently fine to permeate the fabric.

The power of completely permeating a fabric and permanently tinting it under suitable 5 conditions, whether employed practically or not, must therefore be the test of the condition of subdivision sufficient for the successful employment of my invention. Some classes 10 of goods—such as window-shades, book-cloths, &c.—do not require to be tinted so as to be fast against washing, and they may be prepared by my method in a cheaper and simpler manner than when fast goods are desired—that is to say, the scouring and bleaching of the goods 15 may be dispensed with, for while the presence of some oil will to a greater or less extent interfere with the fixation of the color against washing, it will have no effect in preventing the uniform distribution and penetration of 20 the color upon and into the fabric.

When the color has been reduced to a condition or subdivision sufficiently fine to permeate the interstices of the yarn and attach itself to the fiber, it may be applied to cotton 25 or other fabrics by any of the ordinary forms of dye-machines, which consist of vats and rolls arranged so as to pass the goods to be dyed successively through the dye-liquid and through pressure-rolls to remove the surplus 30 fluid and color.

Some of the color compounds with which I have accomplished satisfactory results are the oxides and other insoluble compounds of iron, chromium, aluminum, silicon, manganese, and other elements, as well as a great variety of other compounds.

In practice I have found that while the foregoing method will give results that are satisfactory as far as fastness is concerned, 40 when the color is simply suspended in pure water the affinity of the particles of color for one another seems to have the effect of causing them to aggregate into masses and assemble upon the fabric unevenly, giving it 45 a streaky or blotchy appearance. I have succeeded in rectifying this unevenness in the distribution of color by mixing some gummy or viscous matter with the bath in which the color is held in suspension. The gum seems 50 to have the effect of interposing a resisting medium between the particles of color and preventing its irregular aggregation, or, possibly, lubricating its particles so that they will not adhere to one another. By the use of a 55 viscous bath I am able to get a uniform distribution of the color upon the fabric. The effect of the viscous material upon the color seems to be exemplified by the fact that when the viscous matter is used with the color 60 the fabric must be dried before it will resist the action of water, for the reason that while the fabric remains wet from the first immersion in the color-bath all or nearly all of the color may be removed by washing, while 65 if the fabric be allowed to dry the viscous matter may then be entirely removed by

solvents; but sufficient color will remain fast and permanent to tint the goods, provided the goods have been prepared previously, in the manner heretofore suggested, to remove 70 all substances that would interfere with the permanence of the tinting, and also that the bath shall not contain such substances. If, however, no viscous matter be used, but the color be simply suspended in water, the goods 75 when once immersed will become permanently dyed, and sufficient color to give a good tint will remain fast, whether the goods be dried or not. It will be observed that the same viscous fluid used in the process of subdividing the color may also serve the purpose of securing its distribution upon the fabric—that is to say, the color mixed with gum as it comes from the hands of the color-preparer may at once be put into the dye-vat 80 with the addition of nothing but water and be ready for use. It may, however, happen that a color-bath thus mixed will be too thin and would need for some purposes the addition of more gum to thicken it. 90

The fabric, after having been tinted by the process just described, is dried by any appropriate method. I usually employ heated rolls or drums, over which the fabric is passed. When dried, it is finished in any desired manner by starching, callendering, or beetling. If it is desired to make a soft fabric, the goods, after being dried, may be washed to remove the gum, and then finished in any desired manner. 95

Having thus described my invention, what I desire to claim by Letters Patent is—

1. The herein-described process of tinting yarns and fabrics with insoluble coloring-matter, which consists of subdividing the color 105 until it is fine enough to permeate the interstices of the yarn and attach itself to the individual fibers thereof, then suspending this color in a bath, and passing the yarn or fabric through said bath, as set forth. 110

2. The herein-described process of tinting yarns and fabrics with insoluble coloring-matter, which consists of subdividing the color until it is fine enough to permeate the interstices of the yarn and attach itself to the individual fibers thereof, then suspending this color in an aqueous bath, and passing the yarn or fabric through said bath, as set forth. 115

3. The herein-described process of tinting yarns and fabrics with insoluble coloring-matter, which consists of subdividing the color until it is fine enough to permeate the interstices of the yarn and attach itself to the individual fibers thereof, then suspending this color in an aqueous bath containing gummy 125 or viscous matter, and then passing the yarn or fabric through said bath, as set forth.

VICTOR G. BLOEDE.
